CLAIM

The ornamental design for an ice box, as shown and described.

DESCRIPTION

FIG. 1 is a front, right and top perspective view of an ice box, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is front, right and top perspective view of the ice box shown in an alternate configuration.

The broken lines shown in the drawings are included for the purpose of illustrating portions of the ice box that form no part of the claimed design.

1 Claim, 9 Drawing Sheets
